UNITED STATES PATENT OFFICE

139,679

DESIGN FOR A TOY GUN

Seth Earl Dahlquist, Cadillac, Mich.

Application August 12, 1944, Serial No. 114,855

Term of patent 7 years

(Cl. D34—15)

To all whom it may concern:

Be it known that I, Seth Earl Dahlquist, a citizen of the United States, residing at Cadillac, in the county of Wexford and State of Michigan, have invented a new, original, and ornamental Design for a Toy Gun, of which the following is a specification, reference being had to the accompanying drawing, forming part thereof.

The figure is a perspective view of a toy gun showing my new design, the cord being broken away for convenience of illustration.

I claim:

The ornamental design for a toy gun, as shown.

SETH EARL DAHLQUIST.
